UNITED STATES PATENT OFFICE.

EDWIN WALDRON, OF SCHENECTADY, NEW YORK.

TROLLEY-EAR.

1,214,099.

Specification of Letters Patent. Patented Jan. 30, 1917.

Application filed November 6, 1915. Serial No. 60,115.

To all whom it may concern:

Be it known that I, EDWIN WALDRON, a citizen of the United States, residing at Schenectady, county of Schenectady and 5 State of New York, have invented certain new and useful Improvements in Trolley-Ears, of which the following is a specification.

The invention relates to such improvements and consists in the novel construction and combination of parts hereinafter described and subsequently claimed.

Reference may be had to the accompanying drawings, and the reference characters 15 marked thereon, which form a part of this specification. Similar characters refer to similar parts in the several figures therein.

The principal object of the invention is to provide simple and efficient means for suspending a wire from another wire or cable.

Other objects will appear in connection with the following description.

The invention relates more particularly to devices, sometimes called trolley-ears, 25 whereby a trolley-wire is suspended from a messenger-wire or cable in an electric railway system.

Figure 1 of the drawings is a view in perspective of one form of such device, embodying my invention. Fig. 2 is a view in perspective of one of the clamp-plates detached. Fig. 3 is a view in perspective of the clamp-suspending loop detached. Fig. 4 is a view in perspective of a modification of the construction shown in Fig. 1, having clamp-plates secured together by a single screw-bolt, and the clamp connected with one branch only of the clamp-suspending loop. Fig. 5 is a view similar to Fig. 1, showing 40 another modification of my invention. Fig. 6 is a vertical cross-section of the same taken in the plane of one of the terminals of the clamp-suspending loop. Fig. 7 is a view in perspective of one of the clamp-plates shown in Figs. 5 and 6. Fig. 8 is a view 45 similar to Figs. 1 and 5, showing another modification of my invention. Fig. 9 is a vertical cross-section of the same taken in the plane of one of the terminals of the clamp-suspending loop. Fig. 10 is a view 50 in perspective of one of the clamp-plates, shown in Fig. 9.

Referring to the construction shown in Figs. 1 to 3 inclusive, 1-1 are a pair of 55 clamp-plates preferably formed of heavy sheet-metal and having complementary

jaws, 2-2, adapted to clamp between them a trolley-wire, 3, formed with longitudinal grooves, 4-4, on its opposite sides adapted to receive said jaws. The two clamp-plates 60 are preferably alike, and interchangeable with one another. Each plate is provided with two bolt-holes, 5-5, and with two hook-holes, 6-6, above the respective bolt-holes; and is also provided on its inner side 65 with grooves, 7-7, leading from the upper edge of the plate to the respective hook-holes, 6-6. The two complementary plates, 1-1, are clamped together by screw-bolts, 8-8, passing through the aligned bolt-holes 70 in the two clamp-plates, and nuts, 9-9, on the projecting ends of the respective screw-bolts, to tightly embrace the wire, 3, between the jaws, 4-4. A clamp-suspending 75 loop, 10, whereby the clamp is suspended from a messenger-wire or cable, not shown, is preferably formed of wire bent to substantially U-form with its upper looped end in a plane at right angles to the plane of the clamp-plate, the branches, 11-11, of 80 the loop being bent out of line with one another and inwardly offset at, 12, to bring them in line with the respective openings between the plates formed by the grooves, 7-7, the grooves in one plate being complementary to the grooves in the other to form such 85 openings. The branches, 11, of the wire-loop are bent at right angles in opposite directions to form hooks, 13-13, adapted, when said members are inserted within the 90 groove-formed openings, 7-7, to project in opposite directions, one through a hook-hole, 6, in one of said clamp-plates near one 95 end thereof, and the other through a hook-hole, 6, in the other clamp-plate near the 100 opposite end thereof. The bolts, 8-8, are preferably inserted through the clamp-plates in opposite directions with the heads of the bolts beneath, and in close proximity to, the projecting ends of the respective 105 hooks, 13, whereby said hooks prevent the bolts from turning, as the nuts, 9, are set up. The clamp-plates, 1-1, being alike and interchangeable, only one set of dies is required for their manufacture, and it is practically impossible for the device to be assembled in any but its proper form.

Referring to the construction shown in Fig. 4, the clamp-plates, 14-14, are alike and interchangeable, each being substantially like one-half of the clamp-plate shown in Fig. 2, with a single bolt-hole in each,

and a single hook-hole above said bolt-hole, and with a single opening formed by complementary grooves, 7—7, in the inner sides of the respective plates. A single screw-bolt, 15, serves to clamp the two plates, 14—14, together with their jaws, 2—2, embracing the trolley-wire, 3. In this form of device, I employ a wire-loop, 16, one branch, 17, of which is extended down through the opening formed by the complementary grooves, 7—7, and is bent or offset to form a hook, 18, projecting through the hook-hole in one of the clamp-plates adjacent to the head of the bolt, 15. The other branch 15 of the wire-loop is bent to form an open-hook, 19, adapted to embrace the branch, 17. The hook, 19, can be drawn away from the branch, 17, to permit the loop to be passed over the messenger-wire or cable, after 20 which the hook is sprung back into position to embrace the branch, 17, as shown.

Referring to the construction shown in Figs. 5, 6 and 7, two clamp-plates, 20—20, are employed which are alike and interchangeable, each being provided with two apertures, 24, adapted to align with similar apertures in the complementary plate. The branches, 21—21, of the wire-loop extend down along the outside of the respective 30 clamp-plates and their ends, 22, are inwardly offset and enlarged in diameter extending through the aligned holes in the clamp-plates, their projecting ends being screw-threaded to severally receive a clamp-nut, 23, said clamp-nut, when set up, serving to tightly secure the clamp-plates together with their jaws embracing the trolley-wire, and also serving to securely connect the clamp-suspending loop with the 40 clamp.

Referring to the construction shown in Figs. 8, 9 and 10, two clamp-plates, 25—25, are employed which are alike and interchangeable, each being provided with two bolt-holes, 26—26, and with a hook-hole, 27, above each bolt-hole. The branches, 27—27, of the wire clamp-suspending loop pass down along the outside of the respective clamp-plates, terminating in hooks, 28, 50 which project through aligned hook-holes, 27—27, in the respective plates. Bolts, 29—29, are inserted through the aligned bolt-

holes in the respective clamp-plates which are securely clamped together by the nuts, 30, on the respective screw-bolts. The hook-holes, 27, are in close proximity to the respective bolt-holes, 26, permitting the heads of the respective screw-bolts to be grooved at, 31, to receive the bent portions of the branches of the wire-loop, by which the hooks, 28, are formed, whereby the hooks are securely held in the hook-holes when the nuts, 30, are set up.

The hook-connection, 19, shown in Fig. 4, may be incorporated in the loops shown 65 in any of the other figures, in which case a single branch of the loop would be connected with the clamp in the manner described with respect to such other figure.

What I claim as new and desire to secure 70 by Letters Patent is:

1. A wire-hanger having a wire-clamp provided with a pair of transverse openings, and a clamp-suspending loop with oppositely offset ends extending in opposite 75 directions through the respective transverse openings in the clamp.

2. A wire-hanger comprising a pair of like interchangeable clamp-plates detachably secured together, having wire-engaging 80 jaws and provided with transverse openings, and a clamp-suspending loop having offset ends extending in opposite directions, each through one of said transverse openings.

3. A wire-hanger comprising a pair of like interchangeable clamp-plates provided with bolt-holes, and with hook-holes each located above a bolt-hole, and with complementary grooves in their inner sides 90 forming openings between the plates leading from their upper edge to the respective hook-holes; bolt-connections between said clamp-plates extending through the respective bolt-holes; and a clamp-suspending loop 95 having its branches extending down through the respective groove-formed openings between the plates and its ends offset to form hooks, each engaging one of said hook-holes.

In testimony whereof I have hereunto set my hand this 5th day of November, 1915.

EDWIN WALDRON.
